FRANK DE MINICO, OF WOODCLIFF, NEW JERSEY, ASSIGNOR TO POLLARD-ALLING MANUFACTURING COMPANY, OF NEW YORK, N. Y., A CORPORATION OF NEW YORK.

PLATE-CHAIN-FEEDING MECHANISM.

Application filed March 20, 1926. Serial No. 96,126.

This invention relates to plate-chain feeding mechanisms, such as are employed in printing machines for feeding addressing plates or the like to and away from printing position. The object of my improvements is to provide a mechanism of the character specified, of simple construction and particularly adapted for use in connection with sheet printing machines.

To these ends and others which will be fully set forth later herein my improvements comprise features illustrated in their preferred embodiment in the drawings accompanying this specification, wherein:

Figure 1 is a side elevation, partly in section, of so much of a sheet printing machine as will suffice to suitably show my improvements. Fig. 2 is a plan view corresponding with what is shown in Fig. 1. Fig. 3 is a fragmentary side elevation similar to a portion of Fig. 1, showing the parts in different relative positions. Fig. 4 is a similar elevation showing another step in the operation of the mechanism. Fig. 5 is a sectional end view of a detail of the mechanism. Figs. 6 and 7 are, respectively, a plan and side elevation of a modification of my improved mechanism. The figures of the drawings are all to one scale.

The machine, in connection with which I have chosen to illustrate my improvements, is particularly adapted for printing on one side of single sheets, as 2, from a type form 3, supported on the bed 4 of the machine. Said bed may be supported on the usual legs, as 5, and is provided with carriage 6, adapted for lengthwise traverse over bed 4 and having roller 7 mounted for rotation thereon for bringing sheet 2 into printing

engagement with type form 3 as said roll is caused to traverse thereover. Form 3 may be inked by some known means such as a hand ink roller, or by means of an ink ribbon, not shown. The machine of the drawings is particularly useful for printing circular letters wherein the body of the matter is constant but the superscription variable. To supply this variable superscription is the particular object of the present improvements. The superscriptions or addresses are carried on a series of embossed type-plates, as 8, arranged in the form of a chain 8^a, such for instance, as shown in Figs. 7 to 10 inclusive of U. S. Patent 866,863, of September 24, 1907, to

Hopkins. Said chain of plates may be conveniently carried by reel 9 pivotally mounted in supports, as 10, and thence led through the machine to receiving reel 11 pivotally mounted in supports, as 12.

In printing an address at the head of a letter sheet, it is desirable to have said address relatively near the body of the letter printed from form 3. To this end it is impracticable to have the chain of plates supported in printing position by a roll, as such an arrangement would locate the uppermost plate in printing position too far away from the body of the letter. I therefore employ a swinging platen 13 pivoted at 14 just below the top of table 4, within an opening in the right hand end of said table. Said platen preferably has an adjustable pressure block 15 thereon whereby the height of the plate in printing position may be adjusted by means of push screws 16 and pull screw 17, Fig. 5.

For incrementally advancing plate-chain 8^a, feed drum 18, pivotally mounted at the right hand end of the machine, Figs. 1 and 2, is provided. Said drum has in its periphery, suitably spaced grooves, as 19, for the reception of the plate hinges, as 20, and roll 21, pivotally mounted in supports, as 12, is efficient for keeping said chain in operative engagement with drum 18. Reel 11 may be frictionally driven by known means, not shown, for reeling up the chain as it is advanced by drum 18. Adjacent platen 13 and to the right thereof, roll 22 is pivotally mounted to guide the chain from said platen to drum 18; also roll 23 is mounted between frames, as 5, to guide the chain from reel 9 to platen 13.

For swinging platen 13 and for intermittently rotating drum 18, the following means are provided: Pivoted at 25 below the upper face of bed 4, on ear 24 of said bed, is cam 26 having opposite cam faces 26^a and 26^b for alternate engagement with roll 28 of carriage 6, as that carriage is moved back and forth over bed 4. Depending arm 27 of said cam is pivotally connected at 32 by link 29 with toggle arms 30, 31. The upper end of toggle arm 30 is pivotally connected with ear 33 of platen 13 and the lower end of arm 31 is pivotally connected with ear 34 of leg 5. Fixed to drum shaft 35 is ratchet 36 and turning freely on said shaft is arm 37 having

pivoted thereto pawl 38, spring pressed to engagement with said ratchet. Link 39 connects pivot 32 of link 29 and toggle arms 30, 31 with pawl arm 37. As the movement 5 of link 39 is in excess of the requirements of arm 37 and pawl 38, shoe 40 is provided for said pawl to ride upon at the extreme of its backward movement, see Fig. 3. Also pin 41 is provided to limit the backward movement 10 of toggle arm 31.

In the modification of Figs. 6 and 7, the platen 13 and the chain feed drum 180 are operated from power shaft 42 instead of from carriage 6, as in the earlier figures of 15 the drawings. Also in the arrangement of Figs. 6 and 7 said carriage will be operated by power from said shaft 42, by known means, not shown, and which means are not pertinent to the present improvements. Furthermore the embossed type plates, as 80, 20 of Figs. 6 and 7 are wider than the corresponding plates, as 8, of the earlier figures. For these wider plates it is also preferable to provide feed drum 180 with a plurality of 25 peripheral flat seats, as 43, for the reception of the successive plates 180. In the modification, toggle arms 30, 31 are in all essentials the same as in the earlier figures except that lower link 31 has a downwardly extending 30 arm 310 which is operatively connected to eccentric 44 by strap arm 45. Also, pawl 38 is operated from eccentric 46 fixed to shaft 42, through strap arm 47 pivotally connected to the lower arm of lever 48, pivoted 35 at 49 on frame 5, the upper arm of said lever 48 being connected by link 50 with pawl arm 37. Eccentrics 44, 46 are the operative equivalents of cam 26 and the term cam as used in the claims will be understood to refer 40 equally to said eccentrics.

In some cases, if by any chance the introduction of a sheet is omitted, it is desirable to retain a given plate on platen 13. To this end shoe 40 is carried by arm 51 pivoted on 45 shaft 35. By means of lever 52 pivoted at 53 on frame 5 and operatively connected with arm 51 by pin 54, said shoe 40 may be advanced in clockwise direction under pawl 38 and thereby prevent the engagement of said 50 pawl with ratchet 36.

The operation of my improved mechanism is as follows: In Fig. 1 carriage 6 is shown at the left hand end of the machine, platen 13 is in its dropped position and pawl 38 55 is at the end of its movement in clockwise direction, whereby plate-chain 8^a has just been advanced one plate increment, thereby presenting the next needed plate 8^b over pressure block 15 of platen 13.

A sheet, as 2, ready for printing, is now 60 laid over type form 3 with its right hand end extending over plate 8^b. Carriage 6 is then advanced to the right, roller 7 thereof 65 pressing the sheet down against the type form and said carriage roll 28 presently en-

gages cam face 26^b of cam 26 whereby said cam is oscillated in clockwise direction to the position of Fig. 3, thereby, through link 29 and toggle arms 30, 31, swinging platen 13 upwardly and seating plate 8^b on pressure 70 block 15 and carrying said plate into printing position, Fig. 3. In said figure, roller 7 is shown passing above said plate for pressing the sheet thereagainst. At the same time, link 39 has been drawn to the left, thereby 75 swinging arm 37 in anti-clockwise direction, whereby pawl 38 is retracted onto shoe 40.

The sheet having been thus printed, carriage 6 is started on its return journey to the left, Fig. 4, and presently roll 28 engages 80 face 26^a of cam 26, rocking that cam, whereby link 29 buckles the toggle and withdraws platen 13 downwardly, thereby releasing the plate-chain, and arm 37 is swung in clockwise direction causing pawl 38 to engage 85 ratchet 36.

Carriage 6, continuing its movement to the left, rocks cam 26 its full anti-clockwise stroke, whereby platen 13 is lowered to the position of Fig. 1 and pawl 38 moves ratchet 90 36 and drum 18 to deliver a new plate of 95 chain 8^a over platen 13. The carriage then continues its movement to the left to the position of Fig. 1 and the mechanism is ready to repeat the operation just described.

The operation of the modification of Figs. 6 and 7 is in all essentials the same as described in connection with the earlier figures of the drawings.

I claim:

1. In feeding mechanisms for plate-chains the combination of a chain of type-plates, a type-plate platen mounted for oscillation upwardly for delivering a type-plate into printing position and downwardly for releasing said type-plate, means for intermittently advancing said chain vertically toward and then over said platen, said platen in its upward movement being efficient for delivering an individual type-plate into horizontal 110 printing position.

2. In feeding mechanisms for plate-chains the combination of a chain of type-plates, a type-plate platen mounted for oscillation upwardly for delivering a type-plate into printing position and downwardly for releasing said type-plate, means for intermittently advancing said chain vertically toward and then over said platen including a pivotally mounted chain feed drum, and means for incrementally rotating said drum synchronously with the downward oscillation of said platen.

3. In feeding mechanisms for plate-chains the combination of a chain of type-plates, a type-plate platen mounted for oscillation upwardly for delivering a type-plate into printing position and downwardly for releasing said type-plate, means for intermittently advancing said chain over said platen 125 130

- including a pivotally mounted chain feed drum, a ratchet fixed thereto, an oscillatable pawl for actuating said ratchet, a cam operatively connected with said pawl, and means 5 for synchronizing the downward oscillation of said platen with the movement of said ratchet and drum.
4. In feeding mechanisms for plate-chains the combination of a chain of type-plates, a 10 type-plate platen mounted for oscillation upwardly for delivering a type-plate into printing position and downwardly for releasing said type-plate, means for intermittently advancing said chain over said platen including a pivotally mounted chain feed drum, a ratchet fixed thereto, an oscillatable pawl for actuating said ratchet, means for oscillating said pawl and a shoe pivotally mounted concentric with said ratchet, and 15 means for swinging said shoe between said pawl and ratchet for preventing the coaction of said pawl and ratchet.
5. In feeding mechanisms for plate-chains the combination of a type form bed, a carriage 20 mounted for movement back and forth over said bed, a chain of type-plates, a type-plate platen contiguous to one end of said bed mounted for oscillation upwardly for delivering a type-plate into printing position and downwardly for releasing said 25 type-plate, means for intermittently advancing said chain over said platen including means on said carriage, and means for oscillating said platen downwardly synchronously with the advancement of said chain.
6. In feeding mechanisms for plate-chains the combination of a type form bed, a carriage 30 mounted for movement back and forth over said bed, a chain of type-plates, a type-plate platen contiguous to one end of said bed mounted for oscillation upwardly for delivering a type-plate into printing position and downwardly for releasing said 35 type-plate, means for intermittently advancing said chain over said platen including a pivotally mounted chain feed drum, and means for incrementally rotating said drum synchronously with the downward oscillation of said 40 platen including means on said carriage.
7. In feeding mechanisms for plate-chains the combination of a type form bed, a carriage 45 mounted for movement back and forth over said bed, a chain of type-plates, a type-plate platen contiguous to one end of said bed mounted for oscillation upwardly for delivering a type-plate into printing position and downwardly for releasing said 50 type-plate, means for intermittently advancing said chain over said platen including a pivotally mounted chain feed drum, a ratchet fixed thereto, an oscillatable pawl for actuating said ratchet, an oscillatable cam 55 operatively connected with said pawl, a cam roll carried by said carriage and adapted for oscillating said cam, said cam being operatively connected to said platen for oscillating said platen, and means for synchronizing the downward oscillation of said platen with the movement of said ratchet and drum.
8. In feeding mechanisms for plate-chains the combination of a type form bed, a carriage 65 mounted for movement back and forth over said bed, a chain of type-plates, a type-plate platen contiguous to one end of said bed mounted for oscillation upwardly for delivering a type-plate into printing position and downwardly for releasing said 70 type-plate, means for intermittently advancing said chain over said platen including a pivotally mounted chain feed drum, a ratchet fixed thereto, an oscillatable pawl for actuating said ratchet, an oscillatable cam operatively connected with said pawl, a cam 75 roll carried by said carriage and adapted for oscillating said cam, said cam being operatively connected to said platen for oscillating said platen, means for synchronizing the downward oscillation of said platen with the movement of said ratchet and drum.
9. In a mechanism of the character specified the combination of a type form, a carriage adapted for traverse over said type form, an impression roller on said carriage, means for moving said carriage, a chain of 80 type plates contiguous to one end of said type form, a type plate platen mounted for oscillation on an axis normal to the direction of movement of said carriage, means for intermittently advancing said chain over said platen in the direction of movement of said carriage, the path of movement of said chain of type plates being upward and then horizontal onto said platen, said platen being efficient for delivering an individual 85 type plate from an inclined position to a horizontal position for operation.
10. In feeding mechanisms for plate-chains the combination of a chain of type-plates, a type plate platen mounted for oscillation, means for advancing said chain over said platen, the path of movement of said chain of type plates being upward and then horizontally onto said platen, said platen being efficient for delivering an individual type plate from an inclined position to a horizontal position for operation.

In witness whereof, I hereby affix my signature this 16th day of March, 1926.

FRANK DE MINICO.
